UNITED STATES PATENT OFFICE.

WILLIAM H. WOOD, OF MEDIA, PENNSYLVANIA.

RAILWAY CONSTRUCTION.

1,268,528.

Specification of Letters Patent. Patented June 4, 1918.

Application filed September 13, 1917. Serial No. 191,119.

To all whom it may concern:

Be it known that I, WILLIAM H. Wood, a citizen of the United States, and resident of Media, county of Delaware, and State of Pennsylvania, have invented an Improvement in Railway Construction, of which the following is a specification.

Heretofore steam railways have been constructed with rails having the head and wide base flanges connected by a single vertical web and the rails so formed united by two fish plates placed upon opposite sides of the web and bolted thereto, the abutting rail ends sometimes resting upon a bridge plate 10 placed under the rails and supported upon adjacent cross ties. Constructions of this kind have been found defective in many respects, but more particularly in that the rail sections are not of balanced construction as 15 to stress; and being directly secured to the ties, are liable to premature crystallization and breakage, especially in cold weather when contraction will be at a maximum. Furthermore, the employment of two fish 20 plates arranged upon the outside of the rail web makes it difficult to make and retain rigid union between abutting rail ends.

The object of my invention is to provide a construction of rail section which will be 25 of a balanced form and to so support it on the cross ties that the vibrations induced in the rail in use will be materially relieved, thereby reducing tendency to crystallization to minimum and with a consequent increase 30 in the available life of the rail.

A further object of my invention is to 35 provide a double web rail, in which the union or joint between abutting rail ends is made by a combined bridge and fish plate, 40 the vertical web thereof fitting up into and almost filling the groove between the webs and the base flanges of the webs seating upon the fish plate base in such manner as to be supported vertically and held against 45 lateral spreading. By this construction a strong and durable railway structure is provided and a simple and effective finish secured.

My object is also to provide the double 50 webbed rail with tie plates at each cross tie, which receive the base flanges and space the webs by a shallow rib extending upward between them, the said tie plates and rail

flanges being spiked to the ties, whereby not only are the webs held against spreading, 55 but the base flanges are supported clear of the ties and being separate and forming terminal portions of the webs, they are free to vibrate and release the stresses created in the rail in use, with the result of lessened crystallization and danger of breakage. 60

With the above and other objects in view, the nature of which will be more fully understood from the description hereinafter, the invention consists in the novel construction 65 of railway system as hereinafter more fully described and defined in the claims.

Referring to the drawings: Figure 1 is a side elevation of a railway track showing my improved railway construction; Fig. 2 70 is a plan view of one rail line and adjacent portions of the ties; Fig. 3 is a cross section through the rail and fish plate on a large scale, taken on line 3—3 of Fig. 1; Fig. 4 is a similar cross section through the rail and 75 tie plate, taken on line 4—4 of Fig. 1; Fig. 5 is a perspective view of the fish plate; and Fig. 6 is a perspective view of the tie plate.

2, 2, are the rails and are of arch form in cross section, comprising the head 3 of usual 80 shape and general vertical depth, two vertical webs 4, 4, spaced apart to provide a deep groove 6 between them, and flanged foot portions 5, 5, extending laterally from the bottom of each of the webs. In this construction the webs respectively extend downward from each side of the head and therefore are positioned to directly receive the pounding of the wheels which bear more 85 heavily on one side of the head than the other. This removes the bending strains, which so objectionably come upon the web of the ordinary T-rail now in use. These same benefits are secured irrespective of which side is arranged as the inside of the 90 track in completed condition. The webs 4, 4, being spaced apart and positioned under the head so that no downward thrust can come upon the head to the outside of said webs, it follows that both webs are subjected 95 to compressive strains to the entire elimination of torsional or bending strains, and hence there is less tendency to crystallization and breakage. By the use of two webs, spaced as shown, there is far greater stability 100 of the head against spreading than in

105

the T-rail in present use. It will also be seen that the section thus given to the rail is such that little, if any, more metal is required in its construction than in the standard T-rail, 5 for what may be saved at the base and in the under portion of the head by the presence of the groove 6, will compensate for the additional metal which may be required for the extra web. The fact that there are two webs 10 and that the webs always come under the direct pounding stress, will permit these webs to be of slightly less thickness than the T-rail web for same service, and hence this may also provide for part of the extra 15 web metal required by the presence of two webs instead of one. While economy in cost of metal is not the object of the invention, it is very desirable that the great advantages 20 of my improved rail structure shall be available without any material increase in metal cost.

In the actual rolling of a rail of this shape, no difficulty will arise, as the webs and foot flanges may be rolled as in flat 25 rolling and bent into final position relatively to the head and each other in the final roll "passes." The present costly oblique "passes" in the rolling operation of T-rails may be eliminated and the final shape 30 be secured with a less number of "passes," the advantage of which is directed to a cheapening in the cost of manufacture. It is manifest that this cheapening in cost may be utilized in providing more weight per 35 yard to the rail than is possible with the T-rail section of same cost; and hence at same cost, a stronger and better rail is provided by my improvements.

Not only are the advantages to be seen 40 in the rail *per se*, but also in its association with certain specific forms of fish-plates and tie-plates which greatly strengthen the rail and properly support it by but clear of the cross ties. In Fig. 5, 45 I have shown one of the fish-plates and from it will be seen that there is an inverted T-shaped cross section comprising a vertical web 8 (having holes 12), a flat base or bridging plate 7 providing lateral flanges 50 to each side of the vertical web, and upwardly extending shallow webs or ribs 9, 9, from the extreme outer edges of the base or bridging plate. This construction provides the vertical web 8 as a fish-plate 55 proper, which fits up into the groove 6 of the rail ends, as shown in Fig. 3, where it is bolted rigidly in position by bolts 10, said bolts passing through holes 11 in the rail webs and holes 12 in the fish plate. 60 It will also be seen that the foot flanges 5, 5, of the rail webs fit down upon the base or bridging plate 7 and in the longitudinal grooves formed between the central web 8 and the side webs 9, thereby preventing 65 any spreading of the foot portions of

the webs at the ends of the rail. The heads 14 of the spikes 13, which fasten the rails and fish plates to the cross ties 15, extend over both the flanges 9 and foot flanges 5 of the rail (Fig. 3), and thus hold both of 70 these tightly to the cross tie; and also prevent spreading of the webs, by holding the foot flanges from rising above the retaining flanges 9 of the fish plate structure. It will be noted that the flanges 9 are not notched 75 for the spikes 13, because such is unnecessary to position the base plates 7 since they are already positioned by the bolts 10; and moreover, it is desirable to permit some longitudinal adjustment relatively to the ties 80 and spikes to compensate for possible excessive expansion and contraction of the rails. The holes 12 in the fish plates 8 would be desirably oblong, to allow of expansion and contraction between the rail 85 ends which are held by such plate. The length of the fish plate and bridging base 7 is such that the latter will extend over the space between two adjacent cross ties (Figs. 1 and 2) and rest upon them and in this 90 way fully support the free ends of the rails. It is also evident that the flanges 8 and 9 of the bridging plate 7 strengthen it so that a firm support is thus provided for downward thrust of the rails. Furthermore, as 95 the bolts 10 bind the rails to the web 8, the base plate 7 is as though positively bolted to the rails and thus imparts a rigidity to the rail joint such as cannot be obtained in the rail joints of the T-rail type.

Referring now to the tie plates shown in Figs. 4 and 6, the general cross section is similar to that of the fish plates above described, but with a central web 18 of less height, the same extending only part way 105 up in the groove 6 of the rail as indicated in Fig. 4. In the case of these tie plates, the side webs or ribs 19 at each side of the base plate 17 are notched, as at 20, for receiving the spike shanks 22 to prevent shifting of the plates upon the cross ties when the rails expand and contract longitudinally. The heads 23 of the spikes extend over the foot flanges 5 of the rail so as to hold them down in the side grooves between the flanges 18 and 19, as will be understood from Fig. 4. By use of these tie plates under the rails at each cross tie, the rails will be supported clear of the ties, and the webs 4, 4, of the rails will be prevented from spreading or springing inward toward each other, as might occur if spiked directly to the ties. The construction is such, that in effect, the two webs and their foot flanges are rigidly united at intervals along 115 the length of the rail and thus give a box-like girder construction having great stability and rigidity against bending vertically or laterally.

The general construction of the fish plates 130

and tie plates is of a character that they may be rolled in long lengths and sawed into the definite short lengths required, and hence may be cheaply made. The notches 5 and holes may be punched out, as is customary in metal working.

It will be seen that when the spikes are received in the notches 20 of the tie plates, the entire overhang of the spike heads 23

10 may extend over the foot flanges of the rail and thus more securely hold the rail in position. The notches 20 on opposite sides of the tie plates are in staggered relation, so that the spikes may enter the cross tie 15 out of grain alinement and thereby have less tendency to split the tie or loosen therein.

I have shown the central under portion of both the base 7 of the fish plate and base 17 of the tie plate respectively with longitudinal V ribs 16 and 21, which may embed into the surface of the cross ties to position them, more especially when spiking the rails and plates in position but also as a means of assisting the spikes in holding 25 the rails against displacement in use. The base portions 17 of the tie plates are in length preferably equal to the available width of the cross tie; and in width they exceed the width of the rail at its base and 30 hence provide a greater surface area resting upon the wood of the cross tie and thereby insure greater resistance to wear than where the rail rests directly upon the cross tie. This is especially important in a double web rail of the character herein described.

As a further evidence of strength against spreading, it is pointed out that, not only is the one web with its foot flange held 40 against spreading by the rib 19 of the base and the spike, but the other web is held against shifting in the same direction by the central web 18 of the tie plate and its foot flange from rising by the spike head.

45 From the foregoing, it will be seen that my invention resides, not only in the rail *per se*, but also in its association with the special fish plates and tie plates which reinforce or strengthen the rail when placed in 50 position for use, the whole forming a rail structure of complete form.

Attention is also directed to the fact that the rail shape here set out permits of its ready union with rails of T-cross section 55 by use of fish plates which may be bolted to the outside of the webs; and hence enables the improved rail to be substituted in place of the usual T-rail during normal use of the road bed.

60 It will now be apparent that I have devised a novel and useful construction which embodies the features of advantage enumerated as desirable, and while I have in the present instance shown 65 and described the preferred embodiment

thereof which has been found in practice to give satisfactory and reliable results, it is to be understood that I do not restrict myself to the details, as the same are susceptible of modification in various particulars 70 without departing from the spirit or scope of the invention.

Having now described my invention, what I claim as new and desire to secure by Letters Patent, is:—

75 1. In a railway rail structure, the combination of abutting rails, each comprising a head and two downwardly extending webs therefrom said webs flanged outwardly at the bottom and providing a groove open 80 at the bottom and extending upwardly between the webs to the head, with a fish plate structure comprising a bridging base plate having a longitudinal upwardly extending web in its middle fitting into the grooved 85 portions of the abutting rails and the base plate on each side of its web grooved to receive the flanged portions of the rail, bolts extending through the webs of the abutting rails and the web of the fish plate structure, 90 cross ties upon part of which the bridging base plate rests, spikes driven into the cross ties and having their heads overlapping the bridging base plate and rail flanges for holding them to the ties, a plurality of tie plates 95 under the rails and resting upon the remaining cross ties and each having a web fitting into the groove in the rail and flanges for retaining the rail flanges against spreading, and spikes driven into the cross ties 100 and fitting to the tie plates and also having their heads extending over the rail flanges to hold them and the tie plates in position upon the cross ties.

105 2. In a railway, the combination of two rolled girder rails abutting end to end and having a uniform cross section, said section of inverted U-shape, providing a head and two flanged web portions extending down from the head, the webs spaced apart to 110 provide a longitudinal groove and the flanged portions of the webs extending laterally to provide base flanges for the rail, combined with a plurality of cross ties, a long fish plate structure adjustably secured 115 upon adjacent cross ties and comprising a bridging base plate having a longitudinal upwardly extending web from its middle fitting into the grooved portions of the abutting rails approximately to the top 120 thereof, and the base plate receiving the flanged portions of the webs of the rails, bolts extending through the web portions of the rails and the web of the fish plate structure, a plurality of short tie plates each 125 arranged under the rails and upon the cross ties, said plates comprising a base having a central high web of a shape to fit into the lower portion of the groove of the rails so as to extend approximately half way up 130

and also having side shallow flanges between which and the central web the base flanges of the rail webs fit, and spikes for holding the rail and tie plates securely to 5 the cross ties and with the heads extending over the tie plates and base flanges of the rails.

Copies of this patent may be obtained for five cents each, by addressing the "Commissioner of Patents, Washington, D. C."

In testimony of which invention I hereunto set my hand.

WILLIAM H. WOOD.
